NARROW FABRIC OR THE LIKE

Siegfried L. Oppenheimer, New York, N. Y.

Application May 4, 1950, Serial No. 9,695

Term of patent 7 years

(Cl. D92—1)

To all whom it may concern:

Be it known that I, Siegfried L. Oppenheimer, a citizen of the United States, residing in New York city, in the county of New York and State of New York, have invented a new, original, and ornamental Design for a Narrow Fabric or the like, of which the following is a specification, reference being had to the accompanying drawing, forming part thereof.

The figure is a plan view of a narrow fabric or the like, showing my design.

I claim:

The ornamental design for a narrow fabric or the like, substantially as shown.

SIEGFRIED L. OPPENHEIMER.
